UNITED STATES PATENT OFFICE.

CHARLES C. PFORDT, OF INDIANA, PENNSYLVANIA.

BRICK-PRESS.

1,106,838.

Specification of Letters Patent.

Patented Aug. 11, 1914.

Application filed October 5, 1912. Serial No. 724,080.

To all whom it may concern:

Be it known that I, CHARLES C. PFORDT, a citizen of the United States, residing at Indiana, in the county of Indiana and State 5 of Pennsylvania, have invented certain new and useful Improvements in Brick-Presses, of which the following is a specification.

The present invention relates to improvements in brick presses, and is designed particularly to improve the construction of the 10 brick dies of the standard presses now in use.

By the use of my invention I am now manufacturing brick and paving block by 15 the stiff mud process without the use of oil as a lubricant, thus eliminating all danger of stain from oil on the ware produced. And in using the embodiment of my invention as hereinafter illustrated I have obtained most satisfactory results in shaping 20 the ware in a comparatively perfect manner, and in a quick and economical way. Further, the construction and operation of the brick dies or plungers are eminently 25 satisfactory on account of their simplicity and facile manipulation. Further results attained by the use of my invention are the perfect edges and corners formed on the product.

30 In the accompanying drawings I have illustrated one complete example of the physical embodiment of my invention utilizing steam as the heating element, and a modified form of die press equipped to be heated by either steam or electricity, but both forms of the invention illustrated use the improved construction of liners.

Figure 1 is a view, partly broken away, of 35 one of the upper brick dies or plungers. Fig. 2 is a bottom plan view of Fig. 1. Fig. 3 is a side elevation of Fig. 2 partly in transverse section. Fig. 4 is a modified form of Fig. 3.

The die or plunger 1 is cast of high tempered steel, is hollow to form a heating chamber 1^a, with steam inlet 6 and outlet 7, and is attached to the cross head 4 by means of the bolts 8. The cast metal walls 45 of the die are comparatively thin and this 50 is possible because of the high tempered ma-

terial used. The thinness of the walls of the die provides for an increased radiation of heat on the face of the die, and the presence of the increased heat materially aids in preventing the clay from sticking to the 55 die plate.

One of the particularly novel features of the die resides in the liners. As illustrated in Fig. 2, there are four edge strips or liners to each die, as indicated by the numerals 9 and 10 for the side liners, and 11 and 12 for the end liners. The inner faces of the liners are dovetailed to form a tongue 13 which fits into the complementary groove 14 formed around the recessed edge of the 60 die. These liners are readily replaceable when worn and produce accurate corners and exact edges to the bricks or other ware being manufactured.

In Fig. 4, in addition to the steam heating equipment of the form in Fig. 3, the former die is also provided with a plurality of posts 14' about which are coils of wire 15 through which an electric current may pass to heat the interior of the block 1'. 70 Access may be had to the interior of this block through the door 16, and caps 17 close the steam inlet and outlet ports.

In addition to the elimination of unsightly stains upon the molded brick due to 80 the use of oil, the bricks may be handled easier and with less likelihood of breaking. The full force of the heat penetrates through the comparatively thin bottom of the die block, and its action upon the soft clay 85 product prevents the clay from sticking or adhering to the die.

Should the dovetailed side liners of the dies become worn, they may be easily ground down to fit, and the detachable liners protect the edges against wear, thus reducing 90 the cost of maintenance.

As now constructed many plunger blocks or dies have plates or pads bolted thereto, which become loose and when these loosened 95 parts fail to enter the mold box some portion of the press is broken as a result. But with my construction, the side liner is weaker than the press parts, and if they should contact with the mold box the liner 100

itself would break, and such a break could be mended in a few minutes at an insignificant cost.

Having thus fully described my invention 5 what I claim as new and desire to secure by Letters Patent is:

A rectangular plunger for a brick press having the edges of its working face each formed with an angular recess and a coun-

tersunk dovetail groove, and a detachable 10 liner fitting each recess and formed with a rib locked in the groove.

In testimony whereof I affix my signature in presence of two witnesses.

CHARLES C. PFORDT.
